United States Patent Office

Des. 184,496
Patented Feb. 24, 1959

184,496

TYPEWRITING MACHINE

Raymond Spilman, Darien, Conn., and Roger Engel,
Forest Hills, and Charles A. Jerabek, Bayshore, N. Y.,
assignors to Underwood Corporation, New York, N. Y.,
a corporation of Delaware

Application June 23, 1958, Serial No. 51,464

Term of patent 14 years

(Cl. D64—11)

Figure 1 is a front perspective view of a typewriting machine showing our new design; and

Figure 2 is a rear perspective view.

The dominant features of our design reside in the portions of the machine shown in solid lines.

We claim:

The ornamental design for a typewriting machine, as shown and described.
